UNITED STATES PATENT OFFICE.

ROBERT E. UHL, OF GREENFIELD, OHIO, ASSIGNOR TO PIONEER SUSPENDER COMPANY, A CORPORATION OF PENNSYLVANIA.

SUPPORTER.

Application filed November 3, 1921. Serial No. 512,424.

To all whom it may concern:

Be it known that I, ROBERT E. UHL, a citizen of the United States, residing at Greenfield, in the county of Highland, State of Ohio, have invented a new and useful Supporter, of which the following is a specification.

My invention relates to improvements in a garment supporter, and is applicable to that class of device in which an elastic tension device is utilized.

This invention is a modification or improvement on the invention patented to me by Patent No. 1,344,068, dated June 22, 1920.

In the invention described in said patent I provide means for restraining the tendency of the spring extension or spring loop to spread and extend beyond the margins of the pocket forming means in which said spring is adapted to operate. In such a structure, where the pull on the button loop is straight, or in alignment with the longitudinal extension of the supporting web, the spring extensions will tend to keep properly centered within the margins of the pocket forming device, but where there is a lateral or irregular pull on the button loop, the spring extension tends to assume an inclination to one side or the other of the pocket and even to extend beyond the margins thereof. To prevent such action I have provided means for restraining or limiting the lateral movement of the spring extension as shown in the following drawings, which illustrate, merely by way of example, suitable means for the embodiment of my invention:—

Fig. 1 is an elevation showing a portion of a supporting device embodying my invention with part broken away to show the structure.

Fig. 2 is a vertical section on line 2—2 of Fig. 1.

Fig. 3 is a horizontal section on line 3—3 of Fig. 1.

Similar numerals refer to similar parts throughout the different views.

As will be noted the pocket for holding the spring extension is formed by a simple loop in the webbing 5; as for example the webbing used in forming men's suspenders. The side margins of the webbing forming the pocket are not stitched or otherwise fastened together, so that the pocket is called an open pocket as distinguished from a pocket

that is substantially closed by stitching the side margins together. The strands 6, which either form or are connected to the button loop 7, or other garment engaging device, extend upwardly through eyelets 8 in the lower bend or crease of the webbing, and form an inverted U-shaped loop within the pocket of the webbing. This loop formation is threaded through helical spring extensions 9, properly restrained, as by the connector or yoke 10, to maintain the main extensions of said spring in substantially straight parallel lines.

As above stated, when the pull on the button loop 7 is straight or in alignment with the general extension of the webbing 5, the spring extensions 9 will operate within the margins of said webbing 5; but where there is a lateral pull to the right or the left on button loop 7, there is a tendency to force the upper end of spring extension 9 to one side or the other of the pocket formation; even to the extent of forcing the spring beyond the margins of the webbing, which for a number of reasons is objectionable. To prevent this tendency or action of the spring to become distorted, upon an uneven pull, I provide a guide positioned midway between the two parallel spring extensions 9, and also approximately midway their longitudinal extensions, so that in case the said extensions should tend to rock to the right or left this guide will encounter said extensions and limit their sidewise movement. Such a guide may be in the form of an eyelet 11, passing through the two webbings between the two parallel spring extensions. This eyelet naturally brings the opposite faces of the webbing together and forms a channel on either side of said joinder, which serves as an effective guide for the longitudinal movement of said spring extensions 9, without in any way interfering with said longitudinal movement.

In order that the longitudinal movement shall not be unduly limited by the engagement of the connecting device or yoke 10, I form this connecting yoke 10 with a loop, as at 12, midway its extension. This permits the end portions of member 10, flanking said loop portion, to pass the eyelet the required distance.

What I claim is:—

1. In a supporter, the combination of two elastic parallel strands, a pocket therefor

open as to its longitudinal side margins, formed by two plies of flexible material, a garment engaging device, means for establishing operative relationship between the 5 elastic strands and the garment engaging device, and means forming a guide for maintaining the strands within the margins of the pocket.

2. In a supporter, the combination of two 10 elastic parallel strands, a pocket therefor open as to its longitudinal side margins, formed by two plies of flexible material, a garment engaging device, means for establishing operative relationship between the 15 elastic strands and the garment engaging device, means for maintaining the strands in said parallel relationship, and means forming a guide for maintaining the strands within the margins of the pocket.

20 3. In a supporter, the combination of two elastic parallel strands, a pocket therefor open as to its longitudinal side margins, formed by two plies of flexible material, a garment engaging device, means for establishing operative relationship between the 25 elastic strands and the garment engaging device, and means for connecting the plies together at a point between the parallel strands to form a guide for maintaining the 30 strands within the pocket.

30 4. In a supporter, the combination of two elastic parallel strands, a pocket therefor

open as to its longitudinal side margins, formed by two plies of flexible material, a garment engaging device, means for establishing operative relationship between the elastic strands and the garment engaging device, means for connecting the plies together at a point between the parallel strands to form a guide for maintaining the 40 strands within the pocket, and a yoke for movable connection with the strands to maintain them in parallel relationship, having its intermediate portion in loop formation to permit its strand-engaging ends to 45 pass the point of connection of the plies.

5. In a supporter, the combination of two elastic parallel strands, a pocket therefor open as to its longitudinal side margins, formed by two plies of flexible material, a 50 garment engaging device, means for establishing operative relationship between the elastic strands and the garment engaging device, means for connecting the plies together at a point between the parallel 55 strands to form a guide for maintaining the strands within the pocket, and a yoke for movable connection with the strands to maintain them in parallel relationship, having its intermediate portion recessed to permit its strand-engaging ends to pass the 60 point of connection of the plies.

ROBERT E. UHL.
